UNITED STATES PATENT OFFICE.

WILLIAM A. COMSTOCK, OF CLEVELAND, OHIO.

DESIGN FOR A COILED-WIRE SPRING FOR BEDS, &c.

SPECIFICATION forming part of Design No. 28,896, dated June 21, 1898.

Application filed December 21, 1897. Serial No. 662,941. Term of patent 14 years.

To all whom it may concern:

Be it known that I, WILLIAM A. COMSTOCK, a citizen of the United States, residing at Cleveland, in the county of Cuyahoga and State of Ohio, have invented and produced a new and original Design for Coiled-Wire Springs for Beds and other Household Furniture, of which the following is a specification, reference being had to the accompanying drawings, forming a part thereof.

Figure 1 is a plain elevation of the design, and Fig. 2 is a plan view thereof.

The leading feature of the design consists in the outlines of the spring when viewed in elevation or plan and which is characterized by an outer spiral coil gradually enlarging from top to bottom and an inner spiral coil rapidly diminishing from top to bottom, thus

showing a spring within a spring and both tapered, but in opposite directions.

The outer coil of the design is represented by A and the inner coil by B, and the two coils are blended in a common top circle 2, which determines the top of the design, as well as of both its coils.

What I claim is—

The design for a coiled-wire spring for beds and other household furniture, substantially as herein shown and described.

Witness my hand to the foregoing specification this 24th day of November, 1897.

WILLIAM A. COMSTOCK.

Witnesses:

H. T. FISHER,
R. B. MOSER.
